SNAP FASTENER SOCKET

Michael J. Carpinella, Waterbury, Conn., assignor to Scovill Manufacturing Company, Waterbury, Conn., a corporation of Connecticut

Application April 21, 1952, Serial No. 283,338

1 Claim. (Cl. 24—216)

This invention relates to snap fasteners and more particularly to an improved socket member for snap fasteners.

During recent years there have come into wide use on launderable articles snap fasteners having a socket member as disclosed in the patent to Fenton, No. 2,106,728, February 1, 1938. While such fasteners have been generally satisfactory they have sometimes failed in use because the spring fingers would become distorted laterally or inwardly. This might happen when a strong side pull is applied to the assembled stud and socket members, or if a heavy pressure is put on the stud part when engaged between the fingers and the breast portion of the member.

Some attempts have been made to correct this situation by adding an extra cap member over the socket which itself would take the lateral stress. However, such attempts have not been altogether successful and furthermore they involve an additional part with consequent expense and bulkiness.

The object of my invention is to provide a backing-up of the fingers to prevent their being distorted by lateral stresses and at the same time eliminate the danger of the stud being pushed between the fingers and the breast portion. These purposes are accomplished furthermore without the addition of extra parts and without increasing the bulk or materially increasing the cost of manufacturing.

Socket members of this type are attached to an article of clothing or the like by means of a prong ring, the prongs of which penetrate the clothing and are curled over inside the breast portion. This means that the breast portion should have its inner or anvil wall sloping or curving outwardly and upwardly in a substantially continuous surface so as to insure that the prongs will curl properly inside the breast portion. This has necessitated that the anvil wall be spaced a considerable distance from the free ends of the spring fingers.

According to my invention portions of the anvil wall itself are struck inwardly to provide a backing up means for the spring fingers without interfering with the substantially continuous anvil surface on the inner side of the anvil wall. This is preferably done by making a close double fold or what might also be described as an S-shaped fold of the material of the anvil wall in the vicinity of the free ends of the spring fingers. This not only backs up the fingers against lateral distortion but substantially closes the space between the fingers and the breast portion so that the stud head cannot enter between them.

The foregoing as well as other objects and various features of the invention will be more apparent from a consideration of the following description and accompanying drawing, in which,

Fig. 1 is a sectional view of a snap fastener installation constructed in accordance with the invention and showing a conventional stud assembled thereto.

Fig. 2 is a plan view of the socket member, per se.

2

Fig. 3 is a sectional view of the socket member and the attaching prong ring in unassembled position showing the parts on a larger scale, and

Fig. 4 is a view similar to Fig. 3 showing the attaching prong ring partially assembled to support fabric and the socket member.

Referring to the drawing and first considering Fig. 1, the numeral 10 designates generally a socket member comprising a central circular series of resilient fingers 11 disposed generally parallel to the axis of the assembly and having inwardly directed rolled beads 12 at their free forward ends which are adapted to cooperate with the head 13 and the contracted neck 14 of a stud member 15. An anvil or breast portion 17 is joined to the inner end of the resilient fingers 11 and flares forwardly and outwardly from the rear ends of the fingers and terminates in an annular clinching ring 18 of U shape in cross section. The free edge of the clinching ring 18 is spaced from the inner part of the breast portion to provide an annular opening 19 through which the prongs 20 of an attaching ring 21 may be inserted in the act of assembling the socket member 10 to a support fabric 22.

In order to back up the free ends of the fingers 11 against any severe lateral strains such as might occur when the stud member 15 is assembled to the socket member 10 and the supporting fabrics carrying the stud and socket members respectively are subjected to lateral opposing forces, I provide a rib portion 25 formed outwardly from an intermediate section of the breast portion 17. This rib 25 results from a double or S-shaped fold of metal providing an inner rounded end 27 disposed in relatively close relationship to the free ends of the resilient fingers 11. The relationship of the rib 25 to the fingers should be such as to allow about .004"—.005" clearance therebetween which is sufficient to allow the fingers to freely snap over the head 13 of the stud member 15 and yet prevent the fingers from being stretched beyond their elastic limits.

As specifically shown in Figs. 3 and 4 the upper surface 40 of said breast portion is somewhat flattened and shaped into a conical surface 26 disposed at a relatively small acute angle to the upper plane of the socket member and which conical surface if extended inwardly would be substantially tangent to the upper surface of the beaded ends of the fingers 11. The S-shaped fold does not materially affect the long inclined wall extending from the innermost or leading end of the breast portion 17 to the U-shaped interior of the clinching ring 18 thus assuring that the prongs 20 will be well directed outwardly before they reach the conic surface 26 in the process of assembling the prong ring and socket member to a support. The value of this long outward slope of the anvil portion can be best observed in Fig. 4 showing how the prongs are guided outwardly before reaching the clinching ring 18.

Another important advantage of the invention is the prevention of the head of a stud from wedging in back of the fingers 11 such as might happen in the laundering of a garment. As best shown in Fig. 3 the conic surface 26 is disposed high enough relative to the tip ends of the fingers so as to guide the stud head over the top of the fingers in case one should accidentally line up with any part of the conic surface. Also the rib 25 is so dimensioned as to substantially close up the gap in back of the fingers and prevent the stud head from wedging therein.

This invention is not intended to be limited to the structure herein disclosed for the purposes of illustration but should be regarded as including modifications and variations thereof within the scope of the combined claim.

I claim:

A laundry-proof snap fastener installation of the type

having a socket member adapted for snap engagement with a stud member of circular cross section, which socket member is attachable to sheet-like supporting material by means of a prong ring insertable through the material into engagement with said socket member; said socket member comprising a single piece of sheet metal shaped to provide a plurality of resilient fingers arranged around a central stud receiving opening, the free ends of said fingers being turned radially inwardly to form stud-gripping beads, and a breast portion surrounding said fingers and having its inner lower edge integrally joined to said fingers, said breast portion extending from its inner lower edge in an upward and outward slope and being bent inwardly to provide a continuous rib at its intermediate portion surrounding the beaded ends of said fingers sufficiently close to prevent outward distortion of said fingers beyond their elastic limits, the inwardly bent portion resulting in an interruption in the upward and outward slope of said breast portion providing two distinct anvil surfaces separated by said interruption, the first anvil surface being

relatively steep upwardly and outwardly, and the second anvil surface still sloping upwardly and outwardly but approaching closer to the horizontal plane, said first anvil surface being so sloped and of such length as to cause the prongs of the prong ring to be deflected so as to pass said interruption and strike the second anvil surface with sufficient angularity to effect further outward distortion of said prongs without danger of piercing through said second anvil portion.
